US0D1097028S

(12) **United States Design Patent** (10) **Patent No.:** **US D1,097,028 S**
(45) **Date of Patent:** **** Oct. 7, 2025**

(54) **ALIGNMENT TOOL**

(71) Applicant: **Matthew Janney**, Brea, CA (US)

(72) Inventor: **Matthew Janney**, Brea, CA (US)

(**) Term: **15 Years**

(21) Appl. No.: **29/880,564**

(22) Filed: **Jul. 25, 2023**

(51) **LOC (15) Cl.** **21-02**

(52) **U.S. Cl.**

USPC **D21/791**

(58) **Field of Classification Search**

(57) **CLAIM**

The ornamental design for an alignment tool as shown and described.

DESCRIPTION

FIG. 1 is top perspective view of an alignment tool, showing my new design.

FIG. 2 is a bottom perspective view thereof.

FIG. 3 is a left side elevational view thereof.

FIG. 4 is a right side elevational view thereof.

FIG. 5 is a front elevational view thereof.

FIG. 6 is a rear elevational view thereof.

FIG. 7 is a top plan view thereof; and,

FIG. 8 is a bottom plan view thereof.

1 Claim, 8 Drawing Sheets
